RADIO OPERATED FIRE ALARM

Donald P. Decker, Belmont, Mass.

Application April 8, 1948, Serial No. 19,663

6 Claims. (Cl. 177—366)

1

This invention relates to electrical fire detection and alarm apparatus and particularly to an automatic fire alarm system of the radio operated type comprising a plurality of self-contained, local station, fire detector and fire alarm signal transmitter units located at positions of maximum fire hazard in the protected property, each of which units is so constructed as to generate a signal carrier whenever fire conditions originate in its vicinity, and a central station radio receiver tuned to the same frequency as the signal carrier generated by the transmitter units, said receiver having provision for sounding a fire alarm signal.

Fire detection and alarm equipment hitherto available for use by owners of private residences, smaller business properties, and rural buildings may be identified under two general classifications, namely, (1) wired-in types of central station systems and (2) local alarm units principally operated by clockwork mechanism or dry batteries.

The wired systems are the most highly rated protection and while they have widespread use among the larger commercial properties, the expense associated with their installation has precluded any appreciable use by smaller type property owners. The local alarm devices are inherently limited, as their name implies, and despite lower costs, have also failed to gain extensive use.

The net result of this situation is the almost total absence of fire detection and alarm devices in the majority of smaller residential, rural, and business properties.

Authentic statistics reveal that each year the property losses from fire in the United States increases. A total loss of \$700,000,000 has been estimated for the year 1947. Of the lives lost each year by fire at least two-thirds are casualties in fires occurring in residences and apartments.

The present invention is intended to render available to the smaller property owner a simple, low cost, plug-in type of fire detector and radio operated firm alarm signal transmitter unit which affords a standard of protection comparable to the more expensive forms of wired-in fire alarm systems, but which can be installed in a building by simply plugging the apparatus into the electric light wiring system of said building in the same way that most electrically actuated household appliances are installed, thereby eliminating the necessity of any special wiring for such installation.

2

It is recognized that the general public is accustomed to the use of a wide variety of plug-in devices such as electric irons, toasters, electric clocks, radios, etc. from which fact it is highly probable that a plug-in type of fire detector and radio operated fire alarm should be favorably regarded and result in a wider use of such fire detection equipment by a large number of the owners of smaller type properties which are now exposed to fire hazards.

A primary object of the invention is to provide an improved and simplified form of fire detector and alarm of the class described whose installation consists simply in connecting a plurality of fire detector and radio operated firm alarm signal transmitter units and a radio receiver-alarm unit into the 110-120 volt alternating current electric light wiring system by screw-in or plug-in means at convenient wall plug outlets or light sockets throughout the protected property, said installation thereby being readily accomplished by a layman, without need for expensive skilled assistance or special wiring.

A further object of the invention is to provide a plug-in compact form of radio operated fire alarm signal transmitter unit which is powered from the standard 110-120 volt alternating current electric light wiring system, said unit being so constructed that when rendered operative by an excessive rise in temperature it transmits a carrier signal over the wiring network of said electric light system to a receiver-alarm unit which is plugged into said system at any convenient wiring outlet thereof in a protected property.

A further object of the invention is to provide a form of radio operated fire alarm signal transmitter unit having novel features of design and installation which enable it to be manufactured and sold at moderate prices to owners of small type residences, rural or business properties, which hitherto have been largely unprotected because of the relatively high cost of available wired-in alarm systems.

Another object of the invention is to provide a radio operated fire alarm signal transmitter unit which includes a vacuum tube oscillator having a normally open heater circuit that is closed by a self-contained thermostatic fire detector assembly associated with said vacuum tube, thereby rendering the vacuum tube oscillator operative to transmit a carrier signal whenever a fire condition originates in the vicinity of said transmitter unit.

Another object of the invention is to provide a form of thermostatic switch assembly which constitutes an integral part of a radio operated fire alarm system transmitter unit but which has means for its simple disconnection from the casing of said transmitter unit so that adjustment of the thermostatic switch or substitution of one switch for another can be easily made, thus facilitating the ready inter-changeability and use of a wide choice of commercially available approved types of thermostatic switches according to the option of a user or to fit the protection requirements of a given type of property.

Another object of the invention is to provide a radio operated fire alarm signal transmitter unit having means for the extension of its thermostatic switch circuit to various thermostatic switch units located outside the casing of said transmitter unit when it is installed, for example, in a large cellar or attic area where conventional fire protection practices require an extended coverage by a number of thermostatic switches in a parallel electrical circuit with the switch contained in the housing of said transmitter unit.

Another object of the invention is to provide a self-contained, compact form of radio operated fire alarm signal transmitter unit having simple means embodied therein for the physical location of said unit at high positions with respect to room ceilings in the protected property, in accordance with conventional thermostatic coverage practices for alarm systems of the class described.

Another object of the invention is to provide a radio operated fire alarm signal transmitter unit of such compact size and form as to be capable of inconspicuous installation without sacrifice thereby of effectiveness in operation or its ability to meet the standards required by supervisory agencies with respect to devices of this kind.

Another object of the invention is to provide a radio operated fire alarm signal transmitter unit and a radio receiver alarm unit having means incorporated in both units for the simple test of their operative condition.

A final object of the invention is to provide a radio operated fire alarm transmitter unit having means for avoiding the possibility of false alarms occurring as a result of spurious radio frequency signals originating outside of the protected property.

For a more detailed understanding of the invention, reference is made to the accompanying drawings showing a preferred form thereof in which:

Fig. 1 is a vertical sectional view of the transmitter unit.

Fig. 2 is a section on the line 2-2, Fig. 1.

Fig. 3 is a section on the line 3-3, Fig. 1.

Fig. 4 is a sectional view of an alternate form of casing end cap incorporating a standard male plug for connection with an electric light system standard socket.

Fig. 5 is a view showing installation of a transmitter unit by attachment to a standard electric light ceiling fixture.

Fig. 6 is a view showing installation of a transmitter unit by suspension from the ceiling moulding of a room.

Fig. 7 is a view showing installation of a transmitter unit to a standard electric light system junction box.

Fig. 8 is a perspective view of a terminal mounting strip used in the transmitter unit.

Fig. 9 is a schematic wiring diagram showing

5 a typical installation employing a plurality of transmitter units.

Fig. 10 is a circuit diagram of the radio transmitter.

Fig. 11 is a circuit diagram of the preferred form of receiver-alarm unit.

For convenience I have used the reference character T to indicate the transmitter units and the reference character R to indicate the receiver unit.

As stated above the installation of a fire alarm system embodying this invention in a protected property involves simply the operation of plugging in one or more transmitter units and a receiver unit into various wiring outlet fixtures of the electric lighting system of said property, the transmitter units naturally being located at points of maximum fire hazard.

This is illustrated in Fig. 9 which shows a schematic wiring diagram for a building or protected property and in which 41 illustrates the main wires of the lighting system with the conventional cut-off switch 41a and fuse box 42, and 43 indicates a plurality of branch wiring circuits, each of which is provided with one or more outlet boxes 44 to which lamps, fans, radios or other household appliances are customarily connected.

As illustrated in Fig. 9 one of the transmitter units T embodying my invention is plugged into an outlet box 44 or an electric light socket, in each of the branch circuits, each transmitter unit being located in a position of maximum fire hazard.

The receiver unit R is plugged into one of the outlet boxes 44 and will preferably be so located that when it is actuated, its alarm signal will be most readily heard throughout the property. In many larger residences, the second floor hallway is likely to be the most suitable location for the alarm signal.

The transmitter T which I prefer to use embodies a vacuum tube which is so wired as to form an oscillator circuit designed to produce oscillations of the desired wave length, the power circuit of said tube being connected through a thermostatic switch to the electric light wiring system 41, 43 of the protected property as illustrated in Fig. 9, and the oscillator circuit of said tube being coupled to said wiring system so that the carrier signal sent out from the transmitter unit is transmitted over the wires of the electric light system to the receiver "R".

Fig. 1 shows a preferred form of transmitter unit which comprises a casing 2 preferably cylindrical in form and constructed from plastic material or corrosion-resistant light material such as aluminum, within which is housed the vacuum tube 10 and the elements associated therewith that produce the oscillator circuit shown in Fig. 10.

The cylindrical casing 2 is closed at one end by a base member 4 of insulating material which is shown as screw threaded into the end of the casing as indicated at 3 thereby making a dust tight closure for said end of the casing. The member 4 forms a base on which is mounted the socket 8 for the vacuum tube 10 and also the usual elements associated therewith, such as the coil 5, condenser 6, resistor 7, trimmer condenser 9, etc., so that after the vacuum tube and its associated elements have been mounted on the base 4, the assembly thus formed can be screwed as a unit into the end of the casing.

The socket 8 is shown as mounted on the base

4 by means of screws 11 which extend through holes with which the mounting plate 12 of the socket 8 is provided, said screws being screw threaded into the top of the base 4 and carrying spacer sleeves 13 which position the socket 8 a suitable distance above the base to provide room between the socket and the base for the condensers 6, 9 coil 5, resistor 7, etc.

The base 4 together with the socket supporting screws 11 thus forms a chassis for the tube and its associated parts.

The type of tube employed in this particular embodiment of the invention is a 117 N7GT, a rectifier beam power amplifier with a heater 14 designed for operation directly across a 110-120 volt alternating current circuit. The rectifier portion of the tube is not used as will be seen from the wiring diagram Fig. 10. Tubes of other types may be employed with circuit modifications according to the tube characteristics.

Inductance coil 5 of the tube circuit is shown as mounted on a screw 15 carried by and rising from the base 4, said screw extending through the coil mounting cylinder 16 and the latter being clamped in place by two nuts 17. A terminal mounting strip 18 having two connection lugs 19 affording support for wiring leads from the coil 5 and condenser 6 is shown as being mounted on the upper end of the screw 15.

The condensers 6 and 9 and the resistor 7 may be mounted on the base 4 in any suitable way, preferably by connecting the wire leads or terminals thereof to the proper wiring terminals 20 of the socket 8 and the connection lugs 19 of strip 18.

The wiring is partially omitted from Fig. 1 in order not to confuse the drawing, but the circuit connections are fully shown in Fig. 10.

The base 4 is provided with a pair of wiring connections 21, 21a to which are connected the two wires 22, 23 of a standard line cord 24 by which the transmitter unit is connected to the electric light wiring system of the protected property, said line cord being provided with the usual plug connection 25 adapted to be plugged into any suitable outlet 44 of said wiring system.

The base 4 is also provided with another pair of wiring connections 91 and 92 which will be referred to later.

In order to protect the wiring connections 21, 21a, 91 and 92, and to provide a finished appearance to the end of the transmitter unit, I propose to employ the end cap 26 which is secured to the base 4 by screws 27 and which is provided with a bushing 28 of insulating material through which the line cord 24 extends.

The base 4 is so made that its screw threads 3 are on the upper portion only thereof, the lower portion 29 of said base portion projecting beyond the lower end of the casing 2. The edge portion 30 of the cap member 26 embraces said lower portion 29 of the base 4 and is flush with the casing 2.

Means are preferably provided to conceal the screws 27 so as to prevent loosening of said screws and discourage any unauthorized manipulation thereof, and for this purpose there is shown a plate 31 which overlies the end of the end cap and covers the screws, said plate being held in place by a nut 32 screw threaded to the bushing 28.

On the opposite end of the casing 2 from that carrying the base 4 is mounted a thermostatic switch device 33 by which the operation of the

transmitter unit is initiated whenever fire conditions arise in the vicinity of the transmitter. Any suitable type of thermostatic switch, of which there are many on the market, may be used for this purpose. The thermostatic switch 33 is detachably mounted on the end of the casing so that it can be readily removed for adjustment purposes or so that it can be replaced by another thermostatic switch. For thus detachably mounting the thermostatic element on the casing, I have employed an end cap 34 to which the thermostatic element 33 is detachably mounted, and which in turn is detachably mounted on the casing. The end cap 34 is shown as provided with a skirt 35 which embraces the end of the casing, and it is held in place by attaching screws 36.

The end cap 34 is formed with a central opening 37 to receive the wiring connections 38 of the thermostatic unit, and said end cap 34 is also provided with slots 39 adapted to receive screws 40 by which the thermostat unit is secured to the cap.

By removing the screws 36 the thermostat and cap assembly can be readily removed as a unit from the casing, after which the thermostat can be disconnected from the cap by loosening the screws 40.

In assembling the device, the cap and the thermostat element will first be secured together by the screws 40 and then the wires 23a of the thermostat circuit may be connected to the wiring connections 38, after which the assembled cap and thermostat may be placed on the end of the casing 2 and secured in position by screws 36.

As shown in Fig. 10, the thermostat is connected in series with the heater 14 of the vacuum tube 16 so that normally the heater circuit is open. Whenever fire conditions arise in the vicinity of any transmitter unit, the thermostat associated with said unit will become operative to close the heater circuit thereby activating the vacuum tube oscillator circuit and causing generation of a carrier signal which is superimposed on the electric light wiring system 43 and actuates an associated receiver alarm unit.

The schematic diagram of Fig. 11 shows the wiring of a preferred form of radio receiver-alarm unit. As indicated, a cold cathode gas triode 45 of the OA4G type is wired in the conventional manner with its tuned circuit elements (inductance 46 and capacitance 47) having values effecting impedance matching with the carrier emanating from the transmitter unit of Fig. 10. The controlled circuit of Fig. 11 comprises a relay 48 with protective resistance 49 and capacitance 50, the contacts 51 and 52 of which relay are normally open and in a series circuit which comprises the primary of stepdown transformer 53 connected with the circuit wires 54 by which the receiver unit is connected to the wiring system 41 through any of the usual outlet fixtures 44. The secondary of transformer 53 is in series with a signal device such as alarm bell 60 in a circuit 99. Line voltage in the circuit 54 is controlled by a switch 80 with neon bulb 69 in a parallel electrical circuit serving as a line voltage indicator.

No special claim is made in connection with the receiver unit as such, hence no exact constructional details are shown. However, it will be readily apparent to one conversant with the art, that a small sub-panel supporting the receiver and alarm elements shown in Fig. 11 can be

easily fitted into the standard miniature or table type radio receiver cabinets thus insuring a receiver-alarm unit whose appearance will not disturb the decorative scheme of the most discriminating property owner. It is further evident that with minor adaptations a radio broadcast receiver and electric clock combination could be offered to the using public with the addition of a radio receiver-alarm for the fire detection service thereby providing a single unit of manifold utility.

It is readily apparent that the plug-in feature of said units affords a wide choice of location for effective installation throughout the protected property.

Having located said units, as described, let us assume a fire condition arises in the proximity of one of the transmitter units T. The heat from the fire rises and circulates in the well known manner. The thermostatic switch assembly incorporated in said unit T is responsive to the ambient temperature and has electrical contacts which close when the rate of rise of said temperature exceeds normal or when a predetermined temperature, say 165° F. is reached. This closure of the thermostatic contacts places the normally open heater circuit 14 of vacuum tube 10 across the power line 41 and thus causes the generation of a signal carrier of a frequency determined by the values of inductance 5 and capacitance 6 of Fig. 10. A frequency should be used, 100 kc. for instance, which creates a minimum of harmonic interference with other portions of the radio spectrum. The signal carrier is superimposed upon the electric light wiring network 41, 43, thereby actuating the receiver-alarm unit regardless of where said unit is plugged into said wiring network.

The carrier signal impressed on said wiring network appears across inductance 46 and capacitance 47 of Fig. 11, wherein a cold cathode, gas triode 45 type OA4G is wired in the conventional manner so that the addition of the resonant signal voltage across capacitance 47 increases the negative potential peaks on the cathode and thus increases the potential between the cathode 55 and starter-anode 56.

These peaks start a discharge between the cathode 55 and starter-anode 56. This discharge produces free ions which enable the discharge to transfer to the anode 57 since bleeder resistors 58 and 59 are of such value as to insure that sufficient starter-anode current flows. The normally open circuit of relay 48 with protective resistance 49 and condenser 50 is thereupon closed in turn causing closure of contacts 51 and 52, thus closing the normally open primary circuit of stepdown transformer 53 and thus furnishing operating voltage for the alarm device or bell 60 and sounding the desired warning that a fire condition exists. Extension contacts 91 and 92 provide means for an extension of the alarm circuit if so desired as hereinafter described.

As is commonly known, the magnitude of the carrier signal voltage required to actuate the OA4G tube precludes any false alarm caused by direct radiation from other services in the radio spectrum. Furthermore, the voltage attenuation of the carrier which is an inherent characteristic of this type of application acts to limit its effective use to the wiring network of a given property. Control of the power requirements of both receiver-alarm and transmitter units plus possible use of a line filter or wave trap could serve,

if necessary, as additional means to insure the elimination of interference between adjacent installations.

Provision is made for simple tests to indicate the operative condition of the transmitter units by means of a test button 63 mounted on the casing 2 and having contact terminals 64 and 65 connected in a parallel electrical circuit with the thermostatic switch unit as shown in Fig. 10.

Another similar test button 66 is provided in the receiver-alarm unit as shown in Fig. 11 with contact terminals 67 and 68 providing means for closure of the normally open relay contacts 51 and 52 thereby testing the operation of the alarm device 69.

A neon bulb 69 is also wired across the 110-120 volt alternating current line connection of the receiver-alarm unit thus providing visual means for establishing that line current is being supplied to said unit. If found desirable, a similar voltage indicating neon bulb could be incorporated into the transmitter units by positioning it in a manner similar to test button 63 of Fig. 1 and in a parallel electric circuit with contacts 21 and 21a. It is apparent that these test provisions provide simple means whereby a layman can check the operative condition of a complete system in a protected property.

One of the most serious obstacles to the widespread use of many forms of thermostatic fire detection and alarm devices by owners of smaller properties has been the objection to special, expensive and possibly unsightly wiring required. The present invention offers advantages of a wired system, but eliminates the need of wiring by superimposing a signal carrier on the electric light wiring network. The compact physical dimensions of the radio transmitter unit render possible its efficient yet inconspicuous mounting in a protected property. It is further evident that through the use of a choice of basic colors, the transmitter units can be effectively harmonized with a given room color scheme.

As shown in Fig. 6, the transmitter unit can be suspended from the ceiling moulding 99 of a room by means of a hook 78 attached by screws to bosses 74 of casing 2 and having a curved end which fits snugly over said moulding thus supporting said unit in a horizontal position, close to the moulding in the least conspicuous manner. This form of mounting has two further advantages, namely, location of the thermostatic switch assembly in the uppermost area of a room where, if a fire occurs, the ambient temperature most effectively actuates said switch, and further the line cord connection from said unit may be conveniently extended close alongside of said moulding to the nearest wall plug outlet. Commercially available wire clamps 72 may be inserted under said moulding for a neat and easy installation and minimum disfigurement of the room decoration scheme.

In Fig. 5 another method of installing the transmitter unit is shown, using a clamp 73 screwed to bosses 74 on casing 2 thus affording means to attach said unit to the ordinarily extended portion of the conduit piping 75 of an electric light ceiling fixture 76. In this case as in Fig. 6, the mounting means insures location of the thermostatic switch, associated with said transmitter, in an ideal ceiling location in accordance with conventional fire protection practices.

In Fig. 8 is illustrated the manner of mounting a transmitter unit as a cover to a standard electric light junction box 17 located at a room ceiling. A mounting plate 18 is substituted for cover plate 31 in Fig. 1, and the said unit is fastened to the junction box in the usual manner by screws 19 fitting into tapped holes of the box 17. It is apparent that this form of installation has decided advantages in areas such as cellars or attics and assures conformity with the usual wiring practices.

The transmitter unit may also be constructed to be connected to the electric light wiring system through the medium of an ordinary electric light socket, such a construction being illustrated in Fig. 4 which shows the end cap portion 26 only of the transmitter unit. In this construction the end cap is provided with a fitting 81 having a screw threaded shank portion 82 that extends through the end cap and the protective plate 31, said fitting being secured to the end cap by the nut 32.

The fitting projects beyond the end cap as indicated at 83 and said projecting portion is made with a sleeve contact 84 constructed to screw into an ordinary electric light socket and also with an end contact 85 insulated from sleeve 84, the circuit wires 22, 23 being connected to these contacts and terminating at contacts 21 and 21a of base 4. When a transmitter unit having the end cap construction shown in Fig. 4 is screwed into an electric light socket, it becomes connected to the electric light wiring system and is in condition to function in case fire conditions occur in the vicinity of such electric light socket.

Reference has been made above to the wiring connections 91, 92 carried by the base 4. These wiring connections are connected in parallel with the test button terminals 64, 65 and also with the thermostat wiring connections 38, and they afford means for providing an extension thermostat switch connection by which one or more additional thermostatic switches similar to the thermostat switch 33 can be connected to any transmitter unit T. In some locations, as for instance in an attic or a cellar, it may be desirable to have thermostatic switch devices located at two or three points in the room, and such additional thermostatic switches 33 which are disassociated from a transmitter may be connected to the transmitter through a line cord which is taken through the bushing 28 and connected to the wiring connections 91, 92, the opening through said bushing being made large enough for this purpose.

I claim:

1. A radio-operated fire alarm signaling unit comprising a casing open at opposite ends, a base member of insulating material removably secured to one end of said casing and closing said end, a radio transmitter housed within the casing and mounted on said base member, said base member and transmitter being removable as a unit from the casing, an end cap detachably secured to and closing the other end of the casing, a thermostatic switch element carried by said end cap on the exterior thereof, and means to render the radio transmitter operative to send a radio signal when the thermostatic switch is closed by a rise in the ambient temperature.

2. A radio-operated fire alarm signaling unit comprising a cylindrical casing, a base member of insulating material screw threaded into one end of the casing, a radio transmitter housed

within the casing and mounted on said base member, said base member and transmitter being removable as a unit from the casing, an end cap detachably secured to and closing the other end of the casing, a thermostatic switch element detachably mounted on the exterior of said end cap, and means to render the radio transmitter operative to send a radio signal when the thermostatic switch element is closed by a rise in the ambient temperature.

3. A radio-operated fire alarm signaling unit comprising a cylindrical casing, a base member of insulating material screw threaded into one end of the casing, said base member having a portion projecting beyond the casing end, a radio transmitter housed within the casing and mounted on said base member, the latter and said transmitter being removable as a unit from the casing, a thermostatic switch element detachably mounted on the other end of the casing, means to render the radio transmitter operative to send a radio signal when the thermostatic switch element is closed by a rise in the ambient temperature, an end cap embracing the projecting portion of the base member and having an opening to receive the wire leading to the transmitter, screws connecting said end cap to the base member, and a plate carried by said end cap and both covering said screws and protecting them against unauthorized manipulation.

4. A radio-operated fire alarm signaling unit comprising a casing open at one end, a base element of insulating material closing said open end, a radio transmitter unit, including a vacuum tube, housed within the casing and mounted on said base element, the latter having a pair of wiring connections for connecting a line cord to the transmitter circuits, a thermostatic switch associated with the transmitter and having contacts which are open at normal room temperature but which close at an elevated temperature and also having a pair of wiring terminals through which said contacts are wired in series with the heater element of the vacuum tube, whereby the circuit of the heater element is normally open but is closed to render said vacuum tube operative by a rise in the ambient temperature, and a second pair of wiring connections on said base element for an extension line cord leading to another thermostatic switch remote from the transmitter, said second pair of wiring connections being connected in parallel with the wiring terminals of the first named thermostatic switch.

5. A radio-operated fire alarm signaling unit comprising a casing open at one end, a radio transmitter element within the casing and including a vacuum tube and associated radio components, a chassis supporting said tube and radio components, which chassis comprises a base member of insulating material closing said open end of the casing but removable therefrom, posts rising from the base element, a socket element mounted on said posts and paralleling said base element but spaced therefrom, said associated radio components being mounted on the base between the latter and the socket element, said base together with the chassis and the vacuum tube and associated radio components mounted thereon being removable from the casing as a unit through its open end.

6. A radio-operated fire alarm signaling unit as defined in claim 3, in which the plate carried by the end cap is larger than said cap and con-

11

stitutes the cover of an outlet box of a house wiring system.
